UNITED STATES PATENT OFFICE.

THEODORE SANDHOP AND EDMUND DIEMAR, OF NEW YORK, N. Y.

THERMOMETER-CASE.

SPECIFICATION forming part of Letters Patent No. 717,764, dated January 6, 1903.

Application filed October 17, 1902. Serial No. 127,723. (No model.)

To all whom it may concern:

Be it known that we, THEODORE SANDHOP and EDMUND DIEMAR, citizens of the United States, and residents of New York city, county and State of New York, have invented certain new and useful Improvements in Thermometer-Cases, of which the following is a specification.

This invention relates to a thermometer-case so constructed that the expanded mercury in clinic thermometers can be returned to its normal position past the constriction by centrifugal action and without resorting to jolts or jars. In this way a disagreeable mechanical operation is avoided, the life of the thermometer is prolonged, and its accuracy is maintained.

In the accompanying drawings, Figure 1 is a perspective view of our improved thermometer-case, showing it in operation. Fig. 2 is a side view, partly in section, of the case; Fig. 3, an enlarged longitudinal section through the lower end of the case; Fig. 4, a cross-section on line 4 4, Fig. 3; and Fig. 5, a longitudinal section on line 5 5, Fig. 4.

The letter *a* represents a cylindrical chamber that may be closed at its open end by screw-cap *b* and is adapted for the reception of a clinic thermometer *c*. At its base or closed end the chamber *a* is provided with a pocket *d* of greater diameter and secured thereto by a threaded neck *d'*. The bottom *a'* of chamber *a* forms a partition between the chamber and the pocket and prevents the thermometer from entering the latter.

The pocket *d* is traversed by a spindle *e*, upon which is rotatably mounted a pulley *f*, influenced by a spring *f'*, one end of which is secured to the spindle, while the other end is secured to the pulley. The pulley carries a flexible wire or string *g*, which passes out-

wardly through an opening *d*² in the bottom of pocket *d*. To the free end of string *g* is secured a finger-ring *g'*. The pulley *f* carries a ratchet-wheel *h*, engaged by a detent *h'*, 45 which is influenced by a spring *h*² and is operated by a push-pin *h*³. When the string *g* is drawn outward, the rotation of the pulley *f* winds up the spring *f'*, so that by a subsequent pressure on pin *h*³ the string will be 50 drawn back into the pocket.

In practice a clinic thermometer *c* is, after use upon a patient, placed into the chamber *a*, so that its bulb *c'* is received by cap *b*. The string *g* is now drawn out and the case 55 is quickly rotated around the finger similar to a sling, after which the string is returned to the pocket by depressing pin *h*³. In this way the mercury will be forced outward by centrifugal action and will thus pass the constriction *c*². The result is that the thermometer will be returned to its normal operative condition in a simple, quick, and gentle manner, thus avoiding objectionable physical exertion and also a liability to injure the thermometer itself by sudden jars or jolts. 65

What we claim is—

A thermometer-case provided with a cylindrical chamber which is open at one end and closed at the other end, a cap for closing the 70 open end of the chamber, a perforated pocket at the closed end of the chamber, a spring-influenced pulley within the pocket, and a string carried by the pulley, substantially as specified.

Signed by us at New York city, New York, this 15th day of October, 1902.

THEODORE SANDHOP.
EDMUND DIEMAR.
